UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

PULL SHOVEL.

Application filed August 2, 1924. Serial No. 729,734.

To all whom it may concern:

Be it known that I, PAUL BURKE, a citizen of the United States of America, and resident of Green Bay, in the county of Brown 5 and State of Wisconsin, have invented new and useful Improvements in Pull Shovels, of which the following is a description, reference being had to the accompanying drawings, which are a part of this specification.

10 The invention relates to excavating machines, and more particularly to shoveling machines of the type in which the shovel or dipper is pulled toward the machine during digging, machines of this type being 15 generally employed for digging ditches.

The general object of the invention is to improve upon existing designs of machines of this type by the provision of a box-boom; by so shaping this boom as to provide for a 20 wider range of work as compared to a straight boom of the same length; by so shaping the end of this boom as to permit the dipper stick to swing outwardly to an extended discharging position in a more efficient manner than heretofore; and, by associating with the boom an auxiliary frame 25 operatively connected with the dragline under certain conditions of operation to use the tension in the drag-cable to prevent excessive crowding.

30 The invention further consists in the several features hereinafter set forth and more particularly defined by claims at the conclusion hereof.

35 In the drawings: Fig. 1 is an elevation view of a machine embodying the invention, showing the dragline reeved in one way;

Fig. 2 is a detail plan view of a part of 40 the boom and the dragline arrangement shown in Fig. 1;

Fig. 3 is an elevation view of a machine embodying the invention, showing the dragline reeved in another way;

45 Fig. 4 is a detail plan view of a part of the boom and the dragline arrangement shown in Fig. 3;

Fig. 5 is a detail elevation view of the digging mechanism;

50 Fig. 6 is an end view, partly in section, of the auxiliary frame;

Fig. 7 is an enlarged detail plan view of a medial part of the boom;

Fig. 8 is a detail plan view of the upper end of the dipper stick;

Fig. 9 is a plan view of the dragline 55 sheave;

Fig. 10 is a plan view of the boom, showing the hoist-line arrangement;

Fig. 11 is a section through the boom taken on the line 11-11 of Fig. 5; 60

Fig. 12 is a detail elevation view of a part of the upper end of the boom and dipper handle, showing a modification of the sheaves.

In the drawings the numeral 12 designates 65 the boom vertically pivotally attached at its forked inner end to a hinge-pin 13 supported on a bracket 14 secured to the rotating base 15 of the machine, which base is of well-known construction and mounted on the 70 travelling base 16 of the machine. A prime-mover 17 is mounted on the base 15 and through suitable transmission mechanism drives the propelling treads 18 and actuates the dragline drum 19 and the hoisting drum 75 20. The drums 19 and 20 may be of any suitable construction equipped with clutches and brakes to control their operation, and as shown are axially aligned with each other.

The boom 12 is of box form. By that I 80 mean that both side members 12' are braced rigidly one to the other, there being no intervening division for the passage of the cable or other member therethrough, though the lower forked end is not fully enclosed, 85 as in the main portion, a section of which main portion is shown in Fig. 11. In actual service the boom of this type of machine is subjected to severe torsional stresses arising from eccentric loads on the dipper-lip or 90 teeth when the digging force is applied more forcibly to one side than to the other of the dipper-lip or teeth, and the box-boom efficiently withstands such stresses. By the term "box-boom" I mean a boom in which 95 one side of the boom is braced rigidly to the other side without an intervening slot or channel for the passage of cable.

The boom itself is of cambered form in that its outer end portion 21 extends downwardly from the general plane of the rear part of the boom, and what may be termed the "tip" portion 22 of the portion 21 extends upwardly from the main part of this end portion and carries the pivot-pin 23 for the dipper handle 24. This, it will be observed, has the effect of laterally offsetting the pin 23 below the rear portion of the

boom with the decidedly advantageous result of increasing the digging range of the dipper 25, and the upwardly extending tip permits the dipper handle 24 to swing outwardly the desired amount without interfering with the boom.

The dipper handle 24 has a bracket portion 26 through which the pivot pin 23 passes, and the dipper 25 is preferably substantially rigidly connected to the dipper handle by a pin 27 forming a connection between the lower end of the handle and the rear end of the dipper and by a brace or braces 28 pinned to the forward end of the dipper and the bracket 26. The dipper may be of any suitable construction and is usually provided with digging teeth 28. Chains 29 connected to the sides of the dipper each connect with an arm 30 on the dragline sheave block 31 which is disposed flatwise instead of edgewise.

The upper end of the dipper handle carries a pin 32 and sheave-blocks 33 are directly pivotally mounted on this pin on opposite sides of the handle, see Fig. 8, or the sheaves themselves may be journalled on this pin, as shown in Fig. 12. The extreme inward swinging movement of the upper end of the handle is limited by the handle's contact with a stop-block 34 on the outer end of the boom.

A main frame 35, of any suitable construction, on the rotating base cooperates with an auxiliary frame 36 to support the boom 12 and the digging mechanism associated therewith.

This auxiliary frame 36 is in the form of a box-girder with its lower end 36' mounted on the hinge-pin 13 and its upper end provided with a forked casting 37 carrying a shaft 38 upon which pulleys 39 are loosely mounted, said pulleys being connected with pulleys 40 on the main frame by suitable cables 41 whereby the position of the frame 36 relative to the main frame and operative connection therewith is effected. The upper end of this frame 36 is braced against lateral stresses by adjustable tension braces or rods 42 connecting opposite sides of the casting 37 to the pin 13, the lower ends of said rods being held in spaced position relative to the bracket 14 by suitable spacers 43 on said pin 13.

A guide-sheave 44 for the hoist-line is loosely mounted on the shaft 38 and has an idler sheave 45 associated therewith and carried by arms 46 loose on said shaft. The frame 36 also has brackets 47 carrying a shaft 48 upon which a lifting-sheave 49 for the dragline is mounted.

The boom at its inner end has a fleeting or guide-sheave 50 mounted on a shaft 50' on brackets 50" on the boom with which a fair-lead roller 51 on the pin 13 cooperates. A sheave 52, exterior of the boom, is loosely

mounted on a shaft 52' carried by the boom, and sheaves 53 and 54 are mounted on opposite sides of the boom on a shaft 55 extending through the boom. The boom is also provided with handhole openings 56 in its side and similar openings 57 in the web or brace plates 58 adjacent the shafts 52' and 55 for assembly purposes.

The forked portion of the casting 37 opposite the sheave 44 has a segmented cable-guide-groove 59 over which the dead-end side of the hoisting cable 60 passes.

A hoisting rope sheave-block 61 is pivoted to a bridle 62 loosely mounted on the shaft 38, said sheave being disposed flatwise relative to its arc of swinging.

The hoisting rope or cable 60 is secured to and passes from the hoisting drum 20 over the sheave 44, thence around the sheave of the sheave-block 33 on the left hand side of the dipper handle 24, thence rearwardly and around the sheave of the sheave-block 61, thence forwardly and around the sheave of the sheave-block 33 on the right hand side of the dipper handle, thence rearwardly over the groove 59 and is dead-ended at 63 on the frame 35 of the machine. With this reeving it will be noted that the hoisting cable is used to raise and lower the boom and at the same time cause a swinging of the dipper handle relative to the boom.

The dragline 64 is secured to and passes from the drum 19 under the sheave 50 and over the sheaves 52 and 53 around the padlock sheave 31, thence over the sheave 54 and, in the arrangement shown in Figs. 1 and 2, is then dead-ended directly on the boom, as at 65. In the arrangement shown in Figs. 3 and 4 the dragline, after passing over the sheave 54, passes upwardly over the sheave 49 on the frame 36 and then downwardly to a dead-end point 66 on the boom.

It will be noted from the foregoing that the drag-line straddles the boom and has a two-part-line connection with the dipper 25, and that the hoist-line also works outside of the boom and has a two-part-hoist-line connection with each side of the dipper handle.

In this type of shovel the digging and unloading operations of the dipper are accomplished through the lowering or raising of the boom 12 and the swinging of the dipper 25 relative to the boom, either separately or in conjunction with the movement of the boom through the proper manipulation of the hoist-line 60 and the dragline 64.

Thus, in the construction shown in Fig. 1, the digging operation is effected by the paying out of the hoisting line 60 to lower the boom and swing the dipper 25 outwardly to the digging position shown in full lines, after which the pulling in of the dragline 64 and the gradual release of the hoist-line 60 cause the dipper 25 to swing about the

pivot 23 to effect the digging operation, as shown in dotted lines in this figure. The advantages of the crooked or cambered boom are also apparent from this drawing because if the boom between the points 12 and 23 were straight it will be noted that it would come into contact with the unexcavated material and that as a consequence the dipper 25 could not work at the depth shown. Thus, one of the advantages of this boom is that for a given position of the lower end of the boom, the offset adds materially to the permissible digging depth. Furthermore, if the boom were straight the dipper could not be swung upwardly toward the boom as far as shown because the padlock sheave 31 would contact with the bottom of a straight boom before the dipper ever reached the upper dotted-line digging position shown in Fig. 1, which would, of course, limit the digging range of the machine. Thus, the crooked boom not only permits the dipper working at a greater depth but through a greater range than is possible with a straight boom. As a shovel, it will be understood that the height of the bank or the length of the sweep of the dipper through the material frequently has a controlling effect upon the completeness with which the dipper fills and, therefore, the greater freedom of dipper movement which the cambered boom affords is a marked advantage over the usual straight boom type of machine.

35 From the filled dotted-line position shown in Fig. 1 the dipper is discharged by holding the dragline 64 through the braking of the drag drum 79, then raising the boom by the pulling in on the hoist-line 60 until the dipper clears the bank and then swinging the boom by the turning of the base 15 until the dipper is over the spoil bank at which time the dragline 64 is released or payed out and the weight of the dipper and its contents then swings the dipper outwardly to the discharge position shown in dotted lines in Fig. 1 in connection with the raised boom. As the dipper on discharging swings outwardly with considerable velocity, the upward rise due to the tip 22 gives the upper end of the dipper stick sufficient clearance relative to the boom to permit this swinging action without battering the boom. The stop-block 34 on the boom also limits the extreme inward swing of the upper end of the dipper handle relative to the boom.

As ordinarily employed, the drag cable is dead-ended directly on the boom, as shown in Figs. 1 and 2. In cases of extremely soft material, however, the weight of the boom and dipper is liable to cause excessive crowding of the dipper into the material, thus causing a burying effect which, at times, is great enough to increase the resistance

in pulling the dipper through the material to an amount greater than the power plant can adequately handle. If the drag cable is led back to the machine proper, there will be a lifting moment exerted upon the boom equal to the tension in the cable, multiplied by the length of the perpendicular between the line of the drag cable and the boom hinge 13. This moment can be substantially doubled by passing the drag cable around a 75 sheave journaled on the machine proper, as the sheave 49 on the frame 36 and then dead-ending the cable on the boom, as at 66, shown in Figs. 3 and 4, so that not only does the drag cable swing the dipper about 80 the boom during digging but also tends to lift the dipper and boom.

For shallow digging it is desirable to have the drag cable sheaves farther away from the dipper than the best point for 85 deep digging and this is accomplished in the present machine by changing the location of the shaft 55 for the coaxial sheaves 53 and 54 from its position shown in Fig. 5 to the position where the shaft 54 takes 90 the place of the shaft 52'. Furthermore, it will be noted that the drag cable sheaves 53 and 54 maintain both parts of the dragline parallel to each other for all angular relations between the boom and the dipper 95 stick.

I desire it to be understood that this invention is not to be limited to any particular form or arrangement of parts except in so far as such limitations are specified in the 100 claims or necessitated by the prior art.

What I claim as my invention is:

1. In an excavating machine of the type described, the combination with a support, of a boom pivoted thereon, a dipper and 105 dipper handle pivotally carried at the outer end portion of said boom and swinging toward the same during digging, and cables for controlling the movements of the boom, dipper and dipper handle, said boom being 110 cambered to increase the working range of the dipper.

2. In an excavating machine of the type described, the combination of a support, of a boom pivoted thereon, a dipper and dipper 115 handle pivotally carried at the outer end portion of said boom and swinging toward the same during digging, and cables for controlling the movements of the boom, dipper and dipper handle, the outer end portion of the boom extending downwardly from the main portion of the boom to offset the point of pivotal connection of the dipper handle below the main portion of the boom to increase the working range of the dipper.

3. In an excavating machine of the pull-shovel type in which the dipper and dipper handle are pivoted to the outer end portion of the swinging boom, the improved boom having its outer end portion inclined down- 130

wardly from the main portion of the boom and its tip portion carrying the dipper handle pivot extending upwardly from the main part of said inclined outer portion whereby the working range of the dipper is increased and the dipper handle may swing to discharging position without interfering with the boom.

4. In an excavating machine of the pull-shovel type, the combination with a support, of a boom pivoted thereon, a dipper and dipper handle pivotally carried at the outer end portion of the boom, a padlock sheave connected to the dipper, a dragline passing around said sheave and having its parts straddling the boom, guide sheaves, exterior of and carried by the boom, for said dragline, means for operating said dragline, and means for raising and lowering the boom.

5. In an excavating machine of the pull-shovel type, the combination with a support, of a box-boom pivoted thereon, a dipper and dipper handle pivotally carried at the outer end portion of the boom, a padlock sheave

connected to the dipper, a dragline passing around said sheave and having its parts straddling the boom, guide sheaves, exterior of and carried by the boom, for said dragline, means for operating said dragline, sheaves having their supporting blocks pivoted directly to opposite sides of the upper end of the dipper handle, a hoisting cable having a multi-part hoist line connection with each of said last-named sheaves, and means for operating said hoisting cable.

6. In an excavating machine of the pull-shovel type, the combination with a support, of a boom pivoted thereon, a dipper handle pivotally carried at the outer end portion of the boom, a dipper on the lower end of said handle, sheaves on opposite sides of the upper end of the dipper handle, a frame on said support, a sheave carried by said frame, a hoisting cable having a multi-part hoist line connection with each of the sheaves on the dipper handle and with the sheave on said frame, and means for operating said hoisting cable.

7. In an excavating machine of the pull-shovel type, the combination with a support, of a box-boom pivoted thereon, a dipper handle pivotally carried at the outer end portion of the boom, a dipper on the lower end of said handle, a padlock sheave connected to the dipper and disposed in a plane at right angles to the vertical, a dragline passing around said sheave and having its two parts straddling the boom, guide sheaves, exterior of and carried by the boom, for said dragline, sheaves having

their supporting blocks directly pivoted to opposite sides of the upper end of the dipper handle, a frame on said support, a sheave carried by said frame, a hoisting cable having a two-part hoist line connection with each of the sheaves on the dipper handle and with the sheave on said frame, and means for operating said hoisting cable.

8. In an excavating machine of the type described, the combination with a supporting platform, of a frame mounted thereon, an auxiliary frame associated with the main frame including a frame member, a boom pivoted to the supporting platform, a dipper handle pivotally intermediate its ends to the outer end of said boom, a dipper on the lower end of said handle, a dragline straddling the boom and connected to the dipper, an operating drum on said supporting platform for said dragline, a hoisting drum on said platform, and a hoisting cable on said drum guided over said auxiliary frame and operatively connected with the upper end of the dipper handle.

9. In an excavating machine of the type described, the combination with a support, of a boom pivoted thereon, a dipper having its handle pivotally carried at the outer end portion of said boom and swinging toward the same during digging, and means for controlling the movements of the boom, and dipper, said boom being cambered to increase the working range of the dipper, the greater part of such camber lying within a distance from the outer end of the boom not greater than the distance measured along a straight line from the center of the pivotal connection between the boom and the dipper-stick to the cutting edge of the dipper.

10. In an excavating machine of the type described, the combination with the framework of the machine, of a boom pivoted thereon, a dipper having its handle pivotally intermediate its ends at the outer end portion of said boom, and swinging toward the boom during digging, a hoisting cable associated with the upper end of said handle for raising and lowering the boom and swinging said handle, a drag cable connected with the dipper, and cable connections for the drag cable between said framework and the boom, one at a negligible distance from the boom hinge and the other at a substantial distance from the boom hinge to facilitate the working of the dipper in different kinds of material.

In testimony whereof, I affix my signature.

PAUL BURKE.
